L. B. GREEN

REPEATING FUSE SWITCH

Filed Jan. 20, 1925

UNITED STATES PATENT OFFICE.

LEE B. GREEN, OF LAKewood, OHIO, ASSIGNOR OF ONE-HALF TO CONRAD B. KRAUSE,
OF CLEVELAND, OHIO.

REPEATING FUSE SWITCH.

Application filed January 20, 1925. Serial No. 3,577.

This invention relates to fuse boxes for electrical circuits and more particularly to a type of fuse box in which a plurality of fuses are carried, so as to make it convenient to quickly replace fuses that have blown.

It is one of the objects of the invention to provide a fuse box, of the type referred to, in which there are two separate chambers, one for the unused fuses and the other for the fuse that is being used so that when the latter is blown there will be no liability for the heat or arc to damage the unused fuses.

A further object of the invention is to provide a fuse box, of the type referred to, in which the unused fuses may be quickly and conveniently transferred to the fuse contacts and in which there is a signal device for indicating the presence of a fuse in the contacts, or the absence of a fuse therefrom.

A further object of the invention is to provide a fuse box, of the type referred to, that may be economically manufactured and will be of such simple construction, that there is little or no liability for it to get out of order.

Other objects of the invention and the features of novelty will be apparent from the following description taken in connection with the accompanying drawings, of which:

Figure 1 is a side elevation of a fuse box embodying my invention;

Fig. 2 is a front elevation thereof;

Fig. 3 is a longitudinal section on the line 3—3 of Fig. 1;

Fig. 4 is a longitudinal section on the line 4—4 of Fig. 2;

Fig. 5 is a perspective view of the fuse magazine; and

Fig. 6 is a perspective view of the contacts.

Referring to the drawings, 10 indicates a casing, preferably of a rectangular form and made from molded insulation material. One side of the casing 10 is open and is provided with a cover 11, which is secured in position by the screws 12. The rear wall 13, of the casing, is provided with an opening 14 which serves as a bearing for the journal 15 of the rotatable barrel or member 16. The cover 11 has an opening 17 which serves as a bearing for the journal 18, on the member 16, this

journal projecting beyond the cover 11 and having secured on the end thereof a knob 19. The end of the journal 18 has a boss 20 and this boss has the flattened sides 21. The boss 20 projects into a correspondingly shaped recess 22, in the knob 19, to prevent the knob from turning relatively to the member 16. The knob 19 is secured in position on the journal 18 by means of the screw 23.

A terminal bar 24 is secured in a suitable recess in the rear wall 13, of the casing, by means of the rivets 25. The bar 24 projects above the casing 10 and may carry a binding post 26 or other device to which a wire may be connected. A conductor 27 is connected with the bar 24, as shown in Fig. 4, and extends through a recess 28 in the rear of the wall 13 and along the outer side of the wall 29 of the casing, to the opposite side, and has connected therewith a spring contact member 30, that is best shown in Fig. 6.

A terminal bar 31 is also arranged in a recess in the exterior of the rear wall of the casing and projects below the casing and may carry a binding post 32 or other device for attaching a wire thereto. A contact member 33 is arranged on the interior of the casing, adjacent the rear wall 13, and is connected with the bar 31 by the rivet 34 which extends through the wall 13. The contact members 30 and 33 are so formed as to provide aligned spring seats 35, which are adapted to receive a length of fuse wire 36 and when this fuse wire is in position in the seats 35, the members 30 and 33 are electrically connected so as to complete the circuit from the terminal bar 24 to the terminal bar 31.

The cover 11 is provided with a rectangular opening 37 through which a magazine 38 may be inserted, this magazine being formed of sheet metal, as shown in Fig. 5, and having an opening 39 in the bottom thereof, through which the fuses 40 may be discharged. There is a recess 41, in the outer face of the cover 11, to give access to the tab 42 on the magazine 38. The magazine 38 is supported in suitable recesses, in the inner faces of the wall 13 and the cover 11, and there are channels 43 to receive the ends of the fuses 40 and guide them to pockets 44 in

the periphery of the barrel 16. From Fig. 3 it will be noted that there are four sets of the pockets 44 and that the barrel 16 is hollowed out in the region of these pockets, as indicated at 45, the hollowed out portions 45 being separated by walls 46.

From Fig. 3 it will be observed that the walls 46, that are horizontally disposed, cooperate with ribs 47 and 48 on the side walls 10 of the casing 10, to divide the casing into upper and lower chambers 49 and 50, respectively. It will also be noted, that the magazine 38 is arranged in the upper chamber 49, whereas the contacts 35 are arranged in the 15 lower chamber so that whenever the fuse 36, in the contacts 35, is blown there is no chance for the heat or arc, that is developed, to reach the unused fuses 40.

A shaft 51, extends across the chamber 50 20 and is journaled, at one end, in the wall 13, the other end of this shaft projecting through the cover 11 and carrying a pointer or signal device 52, adjacent the outer face of the cover. Near the middle of the chamber 50, the shaft 51 has secured thereon a dog 53 of non-conducting material, the end of which normally engages with the fuse 36, in the contacts 35. A spring 54 is arranged on the shaft 51 and exerts pressure 30 on the dog 53 to swing the latter toward the right, in Fig. 3, the fuse 36 normally preventing this swinging movement.

On the outer face of the cover 11, I provide the words "In" and "Out", or other 35 suitable indicia, to cooperate with the pointer 52, to indicate the presence of the fuse 36 in the contacts 35, or the absence of a fuse therefrom. When the dog 53 is in the position shown in Fig. 3, the pointer 52 will be 40 positioned as indicated in Fig. 2, to show that there is a fuse 36 in the contacts 35. When the fuse 36 is blown, the spring 54 will swing the dog 53 to the right and carry the pointer 52 into alignment with the word 45 "Out", so as to indicate that there is no fuse in the contacts 35.

The knob 19 is provided, on its face adjacent to the cover 11, with four ratchet teeth 55, with which a spring pawl 56 cooperates.

50 A shaft 57, extends across the chamber 49 and carries a plate 58 on which there is a weight 59, a tongue 60 on the outer end of the plate 58 engaging with the uppermost fuse 40, in the magazine 38, and serving to 55 assist gravity in feeding the fuses downwardly to the barrel 16. The shaft 57 carries, adjacent the outer face of the cover 11, a pointer 61 which cooperates with a series of index marks 62, on the cover 11, to indicate the number of fuses remaining in the 60 magazine 38.

As the parts are illustrated in the drawings, and particularly in Fig. 3, there is a fuse 36 in the contacts 35, so that the circuit through the fuse box is completed. If

the fuse 36 is blown, through overloading the circuit, any unmelted portions of the fuse 36 will drop to the bottom of the casing 10 and may be subsequently removed through the opening 63, which is normally closed by a 70 cover plate 64 that is hinged on the screw 65. The pointer 52 will be automatically positioned, as above described, to indicate that there is no fuse in the contacts 35, such indication being of especial importance, where there are a number of adjacent fuse boxes, as means are thus provided for indicating the particular circuit in which the fuse has been blown. To replace the blown fuse, the knob 19 is turned one-quarter of a revolution, the 75 pawl 56 indicating the proper extent to which the knob should be turned and also preventing backward rotation. This operation rotates the barrel 16, in the clockwise 80 direction, as seen in Fig. 3, and carries the next fuse into the contacts 35. Just before reaching the contacts 35, the fuse will engage with the dog 53 and restore it to the position indicated in Fig. 3, thereby automatically 85 restoring the pointer 52 to the position indicated in Fig. 2, to show that there is a fuse in the contacts 35.

From the foregoing it will be seen that I have provided a comparatively simple device for accomplishing the purposes set forth 90 and that it may be operated to reliably and conveniently and quickly replace a blown fuse.

Having thus described my invention, what I claim is:

1. In a device of the class described, a magazine for a plurality of fuses, a pair of fixed contacts, means for transferring fuses from said magazine to said contacts, and a signal device for automatically indicating 105 the presence of a fuse in said contacts and the absence of a fuse therefrom.

2. In a device of the class described, a magazine for a plurality of fuses, a pair of fixed contacts, means for transferring fuses from said magazine to said contacts, a signal device cooperating with a fuse in said contacts and set by the fuse to indicate its presence therein, and means for automatically 110 actuating said device to indicate the absence of a fuse from said contacts.

3. In a device of the class described, a magazine for a plurality of fuses, a pair of contacts, means for transferring fuses from said magazine to said contacts, a signal device engaged by the fuse in its movement from said magazine to said contacts and set thereby to indicate the presence of the fuse in the contacts, and means for automatically actuating said device to indicate the absence 120 of a fuse from said contacts.

4. In a device of the class described, a casing, a movable member mounted in the casing and dividing the interior thereof into two chambers, a magazine for fuses arranged 125

in one of said chambers, said member being provided with means for transferring fuses from said magazine to the other of said chambers, and contacts in the last-mentioned chamber into engagement with which the fuses are carried by said member.

5. In a device of the class described, a casing, a movable member mounted in the casing and dividing the interior thereof into two chambers, a magazine for fuses arranged in one of said chambers, said member being provided with means for transferring fuses from said magazine to the other of said chambers, and spring contacts in the last-mentioned chamber into engagement with which the fuses are carried and forcibly held by said member.

6. In a device of the class described, a casing, a movable member mounted in the casing and dividing the interior thereof into two chambers, a magazine for fuses arranged in one of said chambers, said member being provided with means for transferring fuses from said magazine to the other of said chambers, and contacts in the last-mentioned chamber into engagement with which the fuses are carried by said member, and means for automatically indicating the presence of a fuse in or the absence of a fuse from said contacts.

7. In a device of the class described, a casing, a movable member mounted in the casing and dividing the interior thereof into two chambers, a magazine for fuses arranged in one of said chambers, said member being provided with means for transferring fuses from said magazine to the other of said chambers, and spring contacts in the last-mentioned chamber into engagement with which the fuses are carried and forcibly held by said member, and means for automatically indicating the presence of a fuse in or the absence of a fuse from said contacts.

8. In a device of the class described, a casing, a rotatable member mounted in the casing and dividing the interior thereof into two chambers, a magazine for fuses arranged in one of said chambers, a pair of contacts in the other of said chambers, said member being provided with means for receiving the fuses from said magazine and carrying them into engagement with said contacts, a member mounted in the same chamber as said contacts and adapted to be engaged by the fuse as it moves into engagement with the contacts so as to be positioned by the fuse, spring means for moving the last-mentioned member to another position when released by the blowing of a fuse in said contacts, and a signal device on the exterior of said casing operatively connected with the last-mentioned member and set thereby to indicate the presence of a fuse in said contacts or its absence therefrom.

9. In a device of the class described, a cas-

ing, a rotatable member mounted in the casing and dividing the interior thereof into two chambers, a magazine for fuses arranged in one of said chambers, a pair of contacts in the other of said chambers, said member being provided with means for receiving the fuses from said magazine and carrying them into engagement with said contacts, a member mounted in the same chamber as said contacts and adapted to be engaged by the fuse as it moves into engagement with the contacts so as to be positioned by the fuse, spring means for moving the last-mentioned member to another position when released by the blowing of a fuse in said contacts, a signal device operatively connected with the last-mentioned member and set thereby to indicate the presence of a fuse in said contacts or its absence therefrom, and means on the exterior of said casing for rotating the first-mentioned member.

10. In a device of the class described, a casing, a rotatable member mounted in the casing and dividing the interior thereof into two chambers, a magazine for fuses arranged in one of said chambers, a pair of contacts in the other of said chambers, said member being provided with means for receiving the fuses from said magazine and carrying them into engagement with said contacts, a member mounted in the same chamber as said contacts and adapted to be engaged by the fuse as it moves into engagement with the contacts so as to be positioned by the fuse, spring means for moving the last-mentioned member to another position when released by the blowing of a fuse in said contacts, a signal device operatively connected with the last-mentioned member and set thereby to indicate the presence of a fuse in said contacts or its absence therefrom, means on the exterior of said casing for rotating the first-mentioned member, and a ratchet device for determining the amount of rotation of the first-mentioned member and for preventing backward rotation thereof.

11. In a device of the class described, a casing, a rotatable member mounted in the casing and dividing the interior thereof into two chambers, there being an opening through the wall of said casing, a magazine adapted to contain a plurality of fuses and so formed as to be adapted to be inserted through said opening, means for supporting said magazine in one of said chambers, said magazine being formed with an opening in one side through which the fuses may be discharged into said rotatable member, a pair of contacts in the other of said chambers to which the fuses are transferred from said magazine by said member, and means for indicating the number of fuses in said magazine.

12. In a device of the class described, a casing, a rotatable member mounted in the

4
casing and dividing the interior thereof into two chambers, there being an opening through the wall of said casing, a magazine adapted to contain a plurality of fuses and so formed as to be adapted to be inserted through said opening, means for supporting said magazine in one of said chambers, said magazine being formed with an opening in one side through which the fuses may be 10 discharged into said rotatable member, a pair

of contacts in the other of said chambers to which the fuses are transferred from said magazine by said member, means for indicating the number of fuses in said magazine, and means for indicating the presence of a 15 fuse in said contacts or the absence of a fuse therefrom.

In testimony whereof I affix my signature.

LEE B. GREEN.
